(57) **CLAIM**

The ornamental design for a base for a coffee pod holder, as shown and described.

DESCRIPTION

FIG. 1 is a perspective view of a base for a coffee pod holder in accordance with my design. The broken lines forming the tiered coffee pod holder in FIG. 1 are for illustrative purposes only and form no part of the claimed design.

FIG. 2 is a perspective view of the base for a coffee pod holder;

FIG. 3 is a top plan view thereof;

FIG. 4 is a front elevational view thereof; and,

FIG. 5 is a bottom plan view thereof.
